UNITED STATES PATENT OFFICE.

EWALD GOLTSTEIN, OF COLOGNE, GERMANY, ASSIGNOR TO AMERICAN GOLDY STOPPER COMPANY, OF SAN FRANCISCO, CALIFORNIA, A CORPORATION OF CALIFORNIA.

APPARATUS FOR APPLYING CAPS TO RECEPTACLES.

1,063,968.

Specification of Letters Patent.

Patented June 10, 1913.

Application filed April 27, 1909. Serial No. 492,522.

To all whom it may concern:

Be it known that I, EWALD GOLTSTEIN, a subject of the King of Prussia, German Emperor, a resident of Cologne, Germany, have 5 invented certain new and useful Improvements in Apparatus for Applying Caps to Receptacles, of which the following is a specification.

My invention relates to applying caps to 10 receptacles by means of a yielding presser made for instance of rubber, according to the general principles disclosed in my U. S. Patents Nos. 743,636 and 812,648. I have found that in practice it is advisable and 15 even necessary in some cases to shield certain portions of the cap from contact with the presser which would otherwise deform said portions or even tear them. For this purpose I have combined with the pressure- 20 exerting part of the apparatus a shield which covers and protects certain portions of the cap.

Reference is to be had to the accompanying drawings in which—

25 Figure 1 is a sectional elevation showing one form of my apparatus in the act of applying a cap to a bottle; Fig. 2 illustrates a slightly different construction before the application of pressure; Fig. 3 is a horizontal section on line 3—3 of Fig. 2 and Fig. 4 is a vertical section showing another form of presser.

35 T indicates a casing or holder provided with a ledge T' forming a seat for the lower surface of the presser G made for instance of rubber. When not under compression this presser has the form of a ring of rectangular cross section as shown in Fig. 2. A cross bar or bridge B is rigidly connected 40 with the casing T by means of a nut or clamping sleeve A, and to the said cross-bar or bridge a block S is secured rigidly as by means of a screw threaded stem S' and a nut C. Between the block S and the casing T 45 is left an annular chamber corresponding to the presser ring G and in this annular chamber a sleeve R is movable up and down, said sleeve having slots R' for the passage of the bridge B. The sleeve can be moved by suitable mechanism not shown, it being obvious that when the sleeve is moved toward the ledge T' the presser G will be forced inward as indicated in Fig. 1, as this is the 50 only direction in which it may expand or

yield. The cap E which is made of sheet 55 metal is placed on top of the bottle F, generally with the interposition of the packing ring or gasket D. As clearly shown in Fig. 1 the block S conforms at its bottom to the shape of the top of the finished cap and is 60 provided with an annular peripheral shield S², which reaches down to the level below that of the packing D. Thus when pressure is applied as indicated in Fig. 1 the presser G cannot reach the level of the gasket D or 65 the top of the cap and exert pressure or other stress upon the upper portion of said cap and thus injury to this portion of the cap is avoided. It is of course understood that the block S bears on the cap with sufficient 70 strength to hold the cap in position while the plunger or sleeve R moves down to press the lower peripheral or mantle portion of the cap into tight contact with the bottle neck. The pressure exerted by the rubber 75 ring G is very great, hence the need of exposing to such pressure only those parts of the cap which are to be forced against the bottle surface. If the presser G were allowed to reach the portion engaged by the 80 packing D, there would be danger of serious injury to this part of the cap.

In the construction illustrated by Figs. 2 and 3 the apparatus has a slightly different formation for the lower end of the block S. 85 This block is made with a chamber S³ to receive a raised portion E' of the cap E², this cap being of the kind shown in my Patent No. 858,174. The block is provided with a shield S⁴ surrounding the chamber S³ and 90 bearing on the top of the cap adjacent to the projection E'. It will be seen that in this construction the upper wall of the chamber S³ does not come in contact with the cap, so that no pressure whatever is exerted on the 95 projection E'. The operation is otherwise the same as in the construction first described, and when compressed the presser G in this case takes a shape somewhat like that shown in Fig. 4. If desired I may employ a presser G² having an internal ridge G² to fit between the shield S⁴ and the cap E². 100

In some cases it is important that the block S should be adjusted accurately in relation to the presser, or in other words, to 105 the ledge T' on which the presser is seated. This is particularly the case when the cap has a form of the character shown in Fig. 2.

In order that the block may be adjusted readily, I may arrange its upper end to screw into the bridge B, the nut C serving to hold the block after adjustment.

5 I claim as my invention:

In an apparatus for applying caps to receptacles, in which a yielding presser is employed, a block, against which the receptacle is pressed in the sealing operation, said block 10 having a flange for inclosing and protecting a portion of the cap from side pressure and

being adapted to be raised or lowered so as to bring the receptacle in the most effective sealing position in relation to the presser.

In witness whereof I have hereunto set my 15 hand in the presence of two subscribing witnesses.

EWALD GOLTSTEIN.
